UNITED STATES PATENT OFFICE.

WALTER PELS, OF NEW YORK, N. Y.

DESIGN FOR A GROTESQUE FIGURE.

Application filed January 21, 1928. Serial No. 24,960. Term of patent 14 years.

To all whom it may concern:

Be it known that I, WALTER PELS, a citizen of the United States, residing at New York, county and State of New York, have invented a new, original, and ornamental Design for a Grotesque Figure, of which the following is a specification, reference being had to the accompanying drawing, forming a part thereof.

Fig. 1 of the drawing is a perspective view of a grotesque figure showing my new design;

Fig. 2 is a front elevational view thereof; and

Fig. 3 is a side elevational view thereof.

The design consists in the grotesque figure shown on the drawings. Its adaptation to various uses is obvious.

I claim as my invention:

The ornamental design for a grotesque figure substantially as shown.

WALTER PELS.
